UNITED STATES PATENT OFFICE

MARY MORGAN-EVANS, OF ROUNDUP, MONTANA

BABY GARMENT

Application filed December 20, 1926. Serial No. 156,008.

This invention relates to the class of apparel and pertains particularly to a garment for infant wear.

The primary object of this invention is to provide a garment designed to take the place of a shirt and the usual abdominal band worn by infants.

The garment embodying this invention contemplates the provision of a back panel 10 and a chest panel having shoulder half-straps on one side while an integral shoulder strap connects the panels upon the opposite side.

The rear panel is provided with band sections which are designed to be folded across the stomach and when the garment is in position three layers of material cover the infant's stomach.

Another object of the invention is to provide a garment of the character described which can be expeditiously and cheaply made up, and which will be quickly and easily donned or removed.

Other objects and advantages of this invention will become apparent as the description of the same proceeds, and it will be best understood from a consideration of the following detailed description taken in connection with the accompanying drawings forming a part of this specification with the understanding however, that the invention is not confined to any strict conformity with the showing of the drawings but may be changed or modified so long as such changes or modifications mark no material departure from the salient features of the invention as expressed in the appended claim.

In the drawings:

Figure 1 shows the garment in front elevation with the band sections connected.

Figure 2 shows the garment in rear elevation.

Figure 3 is a front elevation of the garment showing the band sections disconnected and in opened position.

Figure 4 is a section upon the line 4-4 of Figure 1.

Figure 5 is a vertical transverse section taken upon the line 5-5 of Figure 1.

Figure 6 is a horizontal section through a

portion of the band section showing the manner in which the securing tapes are attached.

Figure 7 is a pattern view of the garment.

Referring now to the drawings in detail wherein like numerals of reference indicate corresponding parts throughout the several views, the numeral 1 indicates the front panel of the garment, the upper portion of each side edge thereof being cut inwardly as indicated by numerals 2 and 3 making this portion of reduced width while the top edge has a curved section cut therefrom as indicated at 4, forming upon one side of the panel the shoulder portion 5 which extends laterally at an acute angle to the length of the panel, while another shoulder portion 6 is formed at the opposite side of the panel which extends substantially parallel to the length thereof, the section cut out at 4 being so designed as to set up a tongue 7 across the shoulder portion 6.

The back panel of the garment is indicated at 8, the top portion of this panel being of slightly less width than the upper portion of the panel 1, as shown in Figure 7, and the top edge of the panel 8 is cut away as indicated at 9 to form the neck encircling section and setting up the straight shoulder strap sections 10 and 11. The section 11 is stitched to the tab 7 of the opposed shoulder strap 6 upon the panel 1, thus bringing the cut out spaces 4 and 9 into opposed relation to form the neck of the garment.

Formed integral with and extending from each side of the panel 8 is an abdominal band end section, which sections are indicated by the numerals 12 and 13, and as shown in Figures 1, 3 and 7 these band sections are materially less in width than the length of the panel of which they form a part.

Each of the shoulder strap portions 5 and 10 has a reinforcing tape 14 sewed transversely thereof and these tapes secure to the strap sections tie tapes 15 by means of which the strap sections 5 and 10 are fastened together.

Set into the lower edge of the back panel 8, approximately at the lines of joinder between this panel and the band sections 12 and 13, are gussets 16, which gussets tend to constrict the lower portion of the garment.

when the band sections 12 and 13 are secured around the body in overlapping relation, as shown in Figures 1 and 2.

5 At the inner end of the band section 12 a reinforcing tape 17 is secured which extends transversely of the band section and secures thereto the ends of a plurality of tie strings or tapes 18.

10 Secured transversely of the other band section, adjacent the free end thereof is a reinforcing tape 19, which secures to this section the ends of a plurality of tie tapes 20.

15 As will be readily understood from a consideration of the drawing taken in connection with the foregoing description, the garment is suspended from an infant's shoulders by means of the shoulder straps 5, 6, 10 and 11 positioning the panels 1 and 8 across the chest and back respectively, after which the band section 12 is folded in across the body 20 and panel 1 and finally the band section 13 is folded over the section 12 and the tapes 18 and 20 tied together as in the manner shown in Figure 1.

25 As shown in Figure 4 three layers of material overlie the abdomen of the infant when this garment is in position.

30 Due to the manner in which the strap 5 extends from the panel 1, when the end of this section is brought against the end of the strap section 10 to be secured thereto, the portion of the panel lying between the straps 5 and 6 will be bowed out giving additional neck and chest space.

35 Having thus described my invention, what I claim is:

An infant undergarment constructed to provide a combined undershirt and abdominal band comprising like companion front and rear panels, each being reduced in width 40 at the upper end to define arm holes, when the panels are placed on an infant and each provided with arcuate portions at their upper edges to define a neck opening, the panels 45 being integrally connected at one side of the arcuate portions by a shoulder strap, shoulder strap extensions on the panels on the other side of the arcuate portions, means detachably connecting the shoulder straps together, abdominal band extensions formed on the opposite sides of the rear panel of the same 50 width as the height of the enlarged portion of the panel, a reinforcing tape secured to one band extension substantially at the juncture 55 of the extension with the rear panel, a reinforcing tape secured to the other band extension adjacent to the free edge thereof, and tying tapes for connecting the band extensions together secured between the binding 60 tapes and the band extensions.

In testimony whereof I affix my signature.
MARY MORGAN-EVANS.
